UNITED STATES PATENT OFFICE.

JOHN W. A. EIMESS, OF NEWARK, NEW JERSEY.

TYPEWRITER ATTACHMENT.

Application filed December 27, 1926. Serial No. 157,349.

This invention relates to typewriters and more particularly to a novel attachment therefor.

The primary object of the present invention is to provide novel means for association with an ordinary type of typewriting machine for normally hiding from view of the operator of the machine, the type bars of the machine.

10 In the constant use of typewriters the movement of the type bars have an injurious effect upon the eyes of the operator of the machine, probably caused by the continuous and rapid movement before the eyes 15 of the operator.

It is therefore another prime object of the invention to provide means for hiding the type bars from view and at the same time permit the means to be moved to such a 20 position, whereby the ribbon can be readily changed when necessary or desirable.

A further object of the invention is to provide a novel attachment for typewriters embodying a supporting plate for connection with the front frame plate of the typewriter directly above the keyboard and a shield pivotally connected with the plate adapted to be normally positioned in front 25 of the type bars with means carried for detachable connection with the upper bar of the typewriter, whereby the shield can be moved into and out of operative position for facilitating cleaning of the type bars.

A still further object of this invention is 35 to provide a sight shield attachment for typewriters of the above character, which will be durable and efficient in use, one that will be simple and easy to manufacture and one which can be placed upon the market 40 and incorporated with a conventional typewriter at a small cost.

With these and other objects in view, the invention consists in the novel construction, arrangement and formation of parts, as will 45 be hereinafter more specifically described, claimed, and illustrated in the accompanying drawings, in which drawings:

Figure 1 is a front elevation of a typewriter showing the improved attachment incorporated therewith,

Figure 2 is a longitudinal side elevation of the typewriter showing the improved attachment incorporated therewith, parts of the typewriter being shown in section to illustrate the detachable connection of the 50 sight shield with the upper cross bar thereof,

Figure 3 is a perspective view of the improved attachment, showing the rear face thereof,

Figure 4 is a detail section taken on the line 4—4 of Figure 3, and

Figure 5 is a view similar to Figure 3 showing the front of the improved attachment.

Referring to the drawings in detail, 65 wherein similar reference characters designate corresponding parts throughout the several views the letter A generally indicates a typewriter and B the novel attachment 70 therefor.

The typewriter A can be of any conventional type and as shown in the present instance illustrates the use of the improved device. The typewriter as shown includes the usual front frame plate 10, board 11, and the 75 upper front cross bar 12.

The improved attachment B can be constructed from any desired material, such as cardboard, light metal or the like and comprises an attaching strip 15 which extends 80 transversely of the front frame plate 10 directly above and in rear of the board 11. This strip 15 can be secured to the frame plate 10 in any desired way, such as by the use of screws 16 which may be part of the assembly screws of the typewriter. Hinged- 85 ly connected to the strip 15 by any desired means, such as by flexible strips 16 is the eye shield plate 17 which extends up from the key board to the top of the typewriter. This shield plate is shaped to conform to 90 the conventional configuration of the typewriter and is cut so as to admit standard parts thereon.

The shield B is held in a raised position 95 in front of the type bars, not shown, in any preferred way, such as by the use of a spring clip 18 embodying resilient arms 19 for engaging the cross upper bar 12 of the typewriter. As shown this resilient clip or fastener extends through the shield 17 and is provided with a knob 20 which constitutes a handle.

Normally the shield is in a raised position 105 as shown in Figures 1 and 2 of the drawings and thus it is evident that the movement of the type bars is hidden by the shield and thus the operator of the machine will be caused no discomfort thereby. When it is desired to clean the typewriter, it is merely necessary to swing the shield 17 to a lowered horizontal position as shown in dotted 110

lines in Figure 2, and it is thus evident that all dirt can be readily removed from the typewriter.

Changes in details may be made without departing from the spirit or scope of this invention, but:

What I claim is:

1. The combination with a typewriter including a front frame plate and a cross bar, 10 an attachment therefor comprising a supporting strip secured to the front frame plate above the keyboard of the typewriter, an opaque shield hingedly connected to the bar, and means carried by the shield adapted 15 to detachably engage the cross bar for normally holding the shield in raised position in front of the type bars.
2. The combination with a typewriter including a front frame plate, a keyboard and 20 a top cross bar, of an attachment for the

typewriter comprising a supporting strip, means securing the supporting strip to the front frame plate above the board, an opaque shield hingedly connected to the upper edge of the supporting strip, and a resilient clip 25 carried by the upper edge of the opaque shield for detachably engaging the cross bar.

3. The combination with a conventional typewriter, an attachment therefor comprising a shield disposed in front of the typewriter in a vertical plane to hide the type bars from view of the operator, means normally holding the shield in a raised operative vertical position, and a hinged connection for permitting the moving of the shield to an inoperative horizontal position for allowing the cleaning of the type bars.

In testimony whereof I affix my signature.

JOHN W. A. EIMESS.
